UNITED STATES PATENT OFFICE.

GUNDER NYGAARD, OF CLERMONT, IOWA.

HYDROCARBON-ENGINE.

1,133,740.

Specification of Letters Patent. Patented Mar. 30, 1915.

Application filed July 20, 1914. Serial No. 852,109.

To all whom it may concern:

Be it known that I, GUNDER NYGAARD, a citizen of the United States, residing at Clermont, in the county of Fayette and State of Iowa, have invented a new and useful Hydrocarbon-Engine, of which the following is a specification.

The present invention appertains to hydrocarbon or internal combustion engines, and relates more particularly to the intake and exhaust valves thereof.

It is the object of the present invention to provide a unique valve structure for a hydro-carbon engine, with a view to obtaining maximum power with a minimum expenditure of fuel, to cheapen the manufacture of the engine, to reduce the number of parts to a minimum, and to enable the parts to be cooled more readily.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein the figure is a sectional view of the improved valve structure as applied to an engine cylinder, parts being shown in full.

In carrying out the invention, the engine cylinder 1 in which the piston 2 reciprocates, is provided with a dome-shaped head or end 3, providing an exhaust chamber therein, and the exhaust pipe 4 is engaged or secured through the dome-shaped head 3 to communicate with the exhaust chamber therein. Between the body of the cylinder 1, and the head 3, there is formed a contracted inner annular valve seat 5, of comparatively large diameter, and in which is seated a puppet valve 6, which forms the exhaust valve. The exhaust valve 6 is seated upon one end of a tubular stem or shank 7 which is slidable through a central opening 8 formed within the head 3.

The tubular stem or shank 7 forms a portion of the intake conduit, the outer end portion of the stem or shank 7 being slidably received by the discharge end of the

intake pipe 9, and a packing or stuffing box 10 being carried by the end of the pipe 9 and embracing the tubular shank or stem 7 to prevent leakage. The end of the intake pipe 9 is concentric or coaxial with the opening 8 of the head 3, in order to properly guide the tubular shank or stem 7 for reciprocatory movement axially of the cylinder 1. The inner end of the tubular stem or shank 7 and upon which the exhaust valve 6 is secured, is flared or formed with a beveled valve seat 11, in which is seatable a puppet valve 12, forming the intake valve, and having a stem 13 projecting axially within the tubular shank 7 of the exhaust valve 6, spiders or apertured guides 14 being secured within the shank 7 and having the stem 13 guided slidably therethrough. A relatively weak coiled wire expansion spring 15 is disposed upon the free end portion of the stem 13 and is seated between the spider or guide 14 remote from the valve 12 and an adjustable nut 16 mounted upon the free end of the stem 13, whereby the spring 15 will normally hold the intake valve 12 seated, although the intake valve may open upon the suction stroke of the piston.

The cylinder 1 is preferably provided with inner ribs 17 adjacent the valve seat 5, for properly guiding the exhaust valve 6 for movement to and from its seat 5, and the ribs 17 are preferably integral with the seat 5, to brace or reinforce the same.

An annular flange 18 is secured upon the protruding portion of the tubular shank 7 outside of the head 3, and a coiled wire expansion spring 19 is disposed upon the shank 7 between the flange 18 and the head 3, to yieldably seat the exhaust valve 6. The exhaust valve 6 may be unseated at the opportune times, in any suitable manner, and to this end, a lever 20 may be fulcrumed to an extension 21 of the head 3, and may have one arm bear against the flange 18, while the thrust or push rod 22 may be fulcrumed to the other arm of the lever 20, to enable the said lever to be actuated by the usual valve shaft (not shown).

As will be obvious, the valve structure is operative notwithstanding the various positions in which the cylinder 1 may be arranged, the cylinder being illustrated in an inverted position in the drawing, although it may be arranged in various other positions in practice. The usual spark plug or igniter 23 is engaged through the cylinder 1

adjacent the valve seat 5, so as to lie between the exhaust valve 6 and the piston 2.

In operation, the exhaust and intake valves 6 and 12, respectively, will normally be held seated under the influence of the respective springs 19 and 15, and when the piston 2 moves through its intake stroke, the suction created within the cylinder will unseat the intake valve 12, and the combustible mixture will then be sucked into the cylinder from the intake pipe 9 through the tubular shank 7 of the exhaust valve 6. Immediately upon the piston 2 reaching the end of the suction stroke, the intake valve 12 will be seated under the influence of the spring 15, and both of the valves 6 and 12 will remain seated during the compression stroke of the piston 2, it being observed that the present engine has a four cycle action. The compressed gas is then ignited by the spark plug 23, as usual, to force the piston 2 through its power or explosion stroke, and then, when the piston 2 returns through its exhaust stroke, the exhaust valve 6 is unseated to enable the burnt gases to pass into the discharge chamber within the dome-shaped head 3 and thence to the atmosphere through the exhaust pipe 4. The exhaust valve 6 may be readily unseated by the timely oscillation of the lever 20, which may be accomplished in any suitable mode, whereby the lever 20 bearing against the flange 18 will slide the tubular shank 7 inwardly against the tension of the spring 19, to unseat the exhaust valve 6, for the purpose indicated. It is to be noted that the intake valve 12 is movable with the exhaust valve 6, since the exhaust valve carries the seat of the intake valve, but in view of the

arrangement and combination of parts described and illustrated, there is no liability of the interference of the fresh and burnt gases.

From the foregoing, taken in connection with the drawing, it will be obvious that the present structure carries out the objects aimed at in a satisfactory manner, and furthermore, it will be noted that the tubular shank 7 of the exhaust valve 6, passing through the discharge chamber within the head 3, will enable the shank 7 to be heated so as to heat the fresh gas entering the cylinder, to increase the efficiency of the engine.

Having thus described the invention, what is claimed as new is:

In an engine, a cylinder having a chambered head at one end and an inner contracted valve seat between the said head and the body of the cylinder, a spring pressed tabular shank slidable through the said head, an exhaust valve carried by the said shank and coöperable with the said valve seat, said shank having a valve seat, a yieldably seated intake valve coöperable with the last mentioned valve seat and carried by the said shank, and means for moving the said shank inwardly to unseat the exhaust valve, there being ribs between the body of the cylinder and first mentioned valve seat forming guides for the exhaust valve.

In testimony that I claim the foregoing as my own, I have hereto affixed my signature in the presence of two witnesses.

GUNDER NYGAARD.
